UNITED STATES PATENT OFFICE.

JAMES T. HOGAN, OF JERSEY CITY, NEW JERSEY, ASSIGNOR TO THE NATIONAL MACHINE COMPANY, A CORPORATION OF NEW YORK.

BUTTONHOLE-SEWING MACHINE.

SPECIFICATION forming part of Letters Patent No. 694,150, dated February 25, 1902.

Application filed June 30, 1899. Serial No. 722,397. (No model.)

To all whom it may concern:

Be it known that I, JAMES T. HOGAN, a citizen of the United States of America, residing in Jersey City, county of Hudson, and State of New Jersey, have invented a new and useful Improvement in Buttonhole-Sewing Machines, of which the following is a specification.

My invention relates to a buttonhole-sewing machine, and has for its object to produce an automatic mechanism by which a buttonhole may be sewed having rows of side and barring stitches, the latter at substantially a right angle to the former, across the ends of the buttonhole-slit.

My invention comprises means to produce, first, a relative feeding movement between the sewing mechanism and the work-support lengthwise of a buttonhole and simultaneously therewith a relative vibratory movement between said devices to sew a row of side or binding stitches; second, means to suspend this relative feeding and vibratory movement, and, third, after the suspension of such movements means to produce a relative feeding movement between the sewing mechanism and the work-support transversely to the length of a buttonhole and simultaneously therewith a relative vibratory movement between said devices to form a row of side or barring stitches.

As one means of accomplishing the object of my invention I have devised the following mechanism, which I will describe and then point out the novel features thereof in the claims.

In the accompanying drawings, Figure 1 is a side elevation of a machine embodying my improvement, a portion of the base being broken away to economize space. Fig. 2 is an end elevation, a cover for certain parts of the needle-operating mechanism being removed and the base being broken away to economize space. Fig. 3 is a plan or top view of certain parts and a horizontal section of others. Fig. 4 is a horizontal section taken partly in a plane indicated by line 4 4 of Fig. 1 and partly in a slightly-higher plane. Fig. 5 is a vertical section in a plane indicated by line 5 5, Fig. 1. Fig. 6 is a vertical section in a plane indicated by line 6 6, Fig. 3. Fig.

7 is a diagram illustrating the position of side stitches and barring-strokes in a buttonhole produced by the machine. It is not, however, intended to indicate the character of 55 the stitchings. Fig. 8 is an inverted plan of the machine. Fig. 9 is a vertical section taken in a plane of the line 9 9, Fig. 8, but with some of the parts in positions different from those they occupy in Fig. 8. Fig. 10 is 60 a vertical section taken partly in different planes, the planes being indicated by line 10 10, Figs. 8 and 3. Fig. 11 is an inverted plan showing cams for imparting certain movements to the work-carrier or cloth-clamp during the formation of barring-strokes. Fig. 12 is an inverted plan on a somewhat-enlarged scale, illustrating a double pawl mechanism. Fig. 13 is an inverted plan of certain cam mechanisms for operating the double pawl 70 mechanism just referred to and another pawl mechanism which serves to rotate the cams which are more particularly shown in Fig. 11. Fig. 14 is an inverted plan illustrating a modification of one of the cams shown in Fig. 11 75 for the purpose of making a somewhat-different disposition of the barring-strokes. Fig. 15 is a diagram of the character of the diagram Fig. 7, but showing a different disposition of barring-strokes resulting from the 80 modified construction illustrated by Fig. 14. Fig. 16 is an inverted plan illustrating a preferred form of the cam-follower which is used in connection with one of the cams shown in Figs. 11 and 14. Fig. 17 is a section on the plane of the line 17 17, Fig. 16. Fig. 18 is an inverted plan showing a modified form of the cams for imparting certain movements to the work-support during the formation of barring-strokes. Fig. 19 is a 90 section on the plane of the line x x, Fig. 18.

Similar letters of reference designate corresponding parts in all the figures.

A designates a sewing-machine head which may be of any suitable form. As shown, it 95 has a base-plate A' and a horizontal arm A². At the end of the arm is fitted a needle-bar A³ in the frame a, the said bar being reciprocated vertically in the usual manner by a crank and pitman actuated by the main driving-shaft B. The frame a is pivoted on studs a² a² to permit of its vibration in the manner

hereinafter described. Adjacent to the needle-bar is fitted a vertically-reciprocating cutter-bar A⁴, to the lower end of which a suitable cutter will be attached.

5 A⁵ designates a well-known form of work-support, consisting of a cloth-carrying plate a⁶ and a foot a⁷, secured to an arm a⁸, which is attached to a plate a⁹, hinged to an upright portion a¹⁰ of a part attached to the work-feed mechanism. Passing through the plate a⁹ and seated at its lower end in the plate a⁶ is a post or stud A⁶, which supports a spring A⁷ between its head and the plate a⁹, which spring serves to hold the foot a⁷ in position to secure 15 the work to the plate a⁶.

A⁸ designates an arm of suitable construction hinged to the bracket a¹⁴, secured to the base-plate and having at its end a¹⁵ a treadle attachment. Forming a part of arm A⁸ is a 20 cam a¹³, which when the treadle is operated depresses the extension a¹² of plate a⁹, thereby raising the foot a⁷ to release the work.

A⁹ designates a stop-piece secured to the arm A⁸, which stop bears against the rear 25 edge of the base-plate.

A¹⁰ designates the shuttle mechanism, which may be of any approved construction, and A¹¹ a pitman for operating the same, said pitman being attached to a crank on the 30 shaft F, actuated by the main driving-shaft by the usual and well-known means.

A¹² designates the usual tension device for the needle-thread. A suitable tension device is also provided for the shuttle-thread.

35 The features above described do not, however, form a part of my invention.

I will first describe the mechanism by which the work-support is fed lengthwise of a buttonhole to sew a row of side stitches, and I 40 will state here that only during such time is the needle-bar given a vibratory movement and also that the mechanism by which the work-support is given its feed and vibratory movements to form the barring-stitches is 45 dormant or inactive.

Immediately below the base-plate of the machine is a plate H, having at its front and rear edges gibs H³, secured thereto by suitable means, as screws h³, which gibs support 50 a plate H'. These plates will be more fully described hereafter, as during the formation of the side stitches they are dormant, and are referred to now as the plate H' supports certain of the parts which impart a lengthwise feed to the work-support during the formation 55 of side stitches.

The plate H' is preferably of the construction shown and has cast therewith, so as to form one integral piece, a tubular hub H² and vertical extensions h' h', all of which extend through suitable slots cut into the base-plate A' and are for the purposes hereafter described.

60 F designates a shaft rotated by suitable gearing in a manner well known from the main driving-shaft B. The shaft F carries at its lower end a cam F', upon which rests

the forked ends of a lever F³, fulcrumed on a stud f³, fixed to the base-plate of the machine.

70 G' designates a pawl-carrying lever fulcrumed on the hub L' of a ratchet-wheel L and receiving motion from the lever F³ through a connecting-link G, the ends of said levers F³ and G' being slotted, as shown, 75 to admit of the adjustment of the link G, by means of set-screws g and g', to vary the throw of the lever G'. The lever G' carries two spring-pressed pawls, only one of which, G³, will be referred to at present, said pawl 80 engaging the teeth of ratchet-wheel L, the hub L' of which is mounted on a boss or projection H⁴ of the plate H'. Secured to and projecting downward from ratchet-wheel L is a pin L⁴, which passes between and engages fingers m⁵ of a plate M⁵, secured by suitable means, as screws m⁶, to a gear-wheel or pinion M². This pinion is supported by its hub in a suitable bracket M³, fastened to the plate H' by means of screws m⁷. A cap-screw 90 M⁴ takes into the hub of pinion M² to hold the latter in position, a friction-washer m⁴ being interposed between the said cap-screw and bracket. The pinion M² engages a pinion M whose hub M' is secured by a pin m or screws 95 to a shaft J', which shaft extends upward through the tubular hub H² of the plate H' and carries at its upper end a feed-disk J, made in the form of a toothed gear-wheel or pinion, either cast with said shaft or separate and fastened thereto by suitable means. The pinion J is provided with a diametrical T-shaped slot J⁵, which receives the head of a screw-bolt j, and over this bolt the end of a 100 pitman J² is passed, being clamped in position by a cap J⁴, engaging the screw-threads of bolt j, said cap, if preferred, having a handle J⁸ to manually operate the pinion J. The pitman J² may be adjusted radially of the pinion J in the slot J⁵ to produce a greater or 105 less traverse of the work-support, according to the length of buttonhole to be sewed.

The plate H', as before described, is provided at one end with the two vertical pieces h' h', which extend upward through a slot 110 A¹³, cut into the base-plate, the upper edges of said pieces being preferably flush with the upper surface of the bed-plate. Into the guideway H⁶ thus formed is a slide-block K, to which is secured the other end of pitman 115 J² by means of a screw J⁶, the end of the pitman J² forming a bearing for the said screw. The slide-block K preferably extends a slight distance above the sides h' h' of the guideway H⁶ and is cut to form a seat for the 120 plate N, which is secured to said block by a screw N'. I have shown the plate N as resting at one end upon a bearing-piece N⁵ and held from vertical displacement by a cap N⁴, secured by screws to the base-plate, although 125 neither of these features is essential. The plate N has secured thereto by screws n an extension N², to which is attached by screws n' the plate a⁶. This latter plate may be slot-

ted at its ends, as shown at $a^{11} a^{11}$, to provide for lateral adjustment. The plates N and N^2 instead of being in two pieces may be made as one.

5 The operation of the feed mechanism so far described is as follows: The rotation of the main shaft B imparts a rocking motion to the lever F³ through cam F' and thence to the pawl-carrying arm G'. By the oscillation of the latter the pawl G³ imparts an intermittent feed to the ratchet-wheel L, which in turn through pin L⁴ rotates the pinions M², M, and J, and the last-named by its connection to slide-block K through pitman J² feeds the plate N and plate a⁶ lengthwise of a buttonhole. During this feed of the work-support the needle is given a vibrating movement transversely to the length of the buttonhole by the mechanism I will now describe.

Secured to the shaft B by suitable means is a bevel-gear B', which engages the gear-wheel B², mounted on a stud b², secured to a bracket b on the arm A². The wheel B² has made integral therewith or separate and attached thereto by suitable means a disk or plate B³, having therein a cam-groove b³, Figs. 1 and 4, engaged by a roller b⁸ on a pin b⁷, which pin is fastened to a lever B⁴, fulcrumed on a stud or shaft b⁴, which extends through the arm A².

B⁵ designates a plate or cover secured by screws b⁵ to the arm A², and this plate is cut away, as shown at b⁶, to provide a clearance for the pin b⁷. A link C is connected to the free end of lever B⁴ and to a bracket or extension d' of a rock-lever D, which latter is fulcrumed at its center on a stud C², Figs. 4 and 5, which stud has a bearing on a plate d³, fastened by screws c³ to the plate B⁵. The plate d³ may, if desired, be cast integral with plate B⁵. The lever D is made with side pieces, as shown, so as to form a longitudinal groove d, and slidably supported therein is a block D', provided with a boss or projection D⁶, on which are mounted the ends of a pitman D⁴ and one end of a link D², a cap-screw D⁵ engaging the boss D⁶ to keep the said pitman and link from being displaced. A guard-plate d⁶, secured to the plate B⁵ by means of screws d⁷, may also be employed to prevent the pitman D⁴ from springing out of position. The bracket d' is slotted, as shown at d⁸, to permit of the adjustment of link C to vary the amplitude of the vibration of the needle.

55 The pitman D⁴ at its forward end has a bearing on a stud a³, set eccentrically on a disk a⁵, provided with a shank a⁴, which is set into an opening in the needle-bar frame a and is held rigidly thereto by means of screws a'. By adjusting the position of shank a⁴, and consequently the stud a³, the pitman D⁴ may be adjusted to compensate for any change of position of the cutter-blade.

65 It will be readily understood from the foregoing description that when lever B⁴ is oscillated a rocking motion is imparted to lever

D, thus reciprocating pitman D⁴ and vibrating the needle-bar A³. This is true except when the end of pitman D⁴ is brought into a position coincident with the fulcrum of lever D, when of course the said pitman would not be reciprocated.

Having thus described the mechanism by which a row of side stitches is sewed, I will now describe the means by which the operation of such mechanism is suspended when barring-stitches are to be formed.

To suspend the vibration of the needle-bar when barring-stitches are to be formed and to determine the position of the end of pitman D⁴ during the sewing of side and barring stitches, I pivot on the boss D⁶ of slide-block D' a link D², which link has secured thereto at its lower end by a screw d⁹ an arm D⁷, which has vertical movement in a suitable guideway D⁸, formed, preferably, by plates d¹⁰ d¹⁰, fastened to a bracket d¹¹, which bracket is secured to the base-plate.

E designates a lever fulcrumed at one end on a stud E', set into a bracket E², fastened by screws e to a plate L⁶, said plate being secured by screws e² to the top of hub H² of plate H'. The other end of lever E is slotted at e' and is secured by means of set-screw D⁹ to the vertically-movable arm D⁷, the slot e' providing a clearance for screw D⁹ during the barring operation.

E³ designates a cam-follower secured to lever E by screws e³, which follower rests upon the cam I', now to be described.

The pinion J, as before described, is secured to the upper end of shaft J'. This shaft passes through the opening in the plate L⁶, as indicated by dotted lines in Fig. 9. Engaging the pinion J is a pinion I, mounted on a stud I⁸, secured to the plate L⁶. The said pinion carries on its upper face a three-step cam I', having the cam-surfaces I² I³ I⁴ I⁵. A cap-screw I⁶, taking into the stud I⁸, and a washer I⁷, interposed between the head of said screw and said cam, holds the cam and pinion in frictional engagement with the plate L⁶. The cam I' is slotted, as shown at i' i', to permit of its adjustment on pinion I, and set-screws i² i², taking into openings in the face of said pinion, hold the cam I' in position on the pinion.

In Figs. 1, 3, 4, and 5 the parts are shown in position at the beginning of a row of side stitches, with the point of connection between pitman D⁴ and rock-lever D above the fulcrum C² of the latter, so that upon rotation of shaft B a vibratory movement is given the needle-bar, as before explained. During the sewing of the first row of side stitches the cam I' is so adjusted that the face I² supports the follower E³, and consequently the arms D⁷, link D², slide-block D', and pitman D⁴, in the positions shown until said row of side stitches has been completed, at which time the follower E³ falls from the face I² and rests upon the face I³, the face I² passing from under the said follower on the movement of

the feed-wheel in forming the last of the side stitches. The vertical distance i^3 from the face I^2 to face I^3 is such that the fall of follower E^3 lowers lever E , and consequently the end of pitman D^4 on slide-block D^7 , until said end is in a position coincident with the fulcrum C^2 of rock-lever D , and hence no movement whatever is imparted to pitman D^4 to vibrate the needle-bar. As rotation of pinion J is also suspended during the formation of barring-stitches, as will be fully described, rotation of pinion I and cam I' ceases at the same time and the end of pitman D remains as above stated until the end of the barring operation, when by the advancement of ratchet-wheel L one or two teeth at the beginning of its movement to form the second row of side stitches the pinion I is rotated to carry the face I^3 from under the follower E^3 and to permit said follower to fall to the face I^4 , over which it travels during the formation of the second row of side stitches. The vertical distance i^4 between the faces I^3 and I^4 is equal to the vertical distance i^3 , so that when the follower E^3 passes the face I^4 the end of pitman D^4 is brought below the fulcrum C^2 of rock-lever D a distance equal to that at which it was above during the formation of the first row of side stitches if the two rows are to be of the same width, as is the usual practice, and hence to a position that the said pitman will be reciprocated to give a vibratory movement to the needle-bar in the same manner as heretofore described with reference to the first row of side stitches. When the follower E^3 is brought to the end of face I^4 , it will be raised by the inclined face i^5 during the movement of ratchet-wheel L in the formation of the last of the side stitches, so as to rest on the face I^5 during the formation of the second set of barring-stitches. This movement again brings the end of pitman D^4 to a position coincident with the fulcrum C^2 and suspends the vibration of the needle-bar in the same manner as before described with reference to the first set of barring-stitches. At the end of the second barring operation the follower E^3 is raised by the inclined face i^6 to the face I^2 in position to begin the sewing of a row of side stitches on another buttonhole.

I have shown a spring D^{10} , secured at one end to the arm D^7 and at its other to the base-plate or to the bracket d^{11} , to hold the follower E^3 in positive engagement with the different faces of cam I' . I do not wish to be understood as limiting myself to the precise construction of cam shown to effect the adjustments of the end of pitman D^4 with respect to the fulcrum of rock-lever D , as any form of cam to produce this effect is within my invention.

I have heretofore described the means by which the work-support is fed lengthwise of a buttonhole and the needle-bar given a vibratory movement during the sewing of a row of side stitches and the means to control

the position of the pitman D^4 during the formation of both side and barring stitches. Having reached the end of a row of side stitches, it is necessary to suspend the lengthwise feed of the work-carrier plate, as well as the vibration of the needle-bar, and I will now describe the means by which the former result is produced, it being understood that at the end of the first row of side stitches the needle is at the center of the buttonhole-slit or on a line in continuation thereof and the follower E^3 is on the face I^3 of cam I' to throw the end of pitman D^4 to a position coincident with fulcrum C^2 of rock-lever D .

L^2 designates a plate located below the ratchet-wheel L . It has a bearing on the reduced end L^8 of hub H^4 and is held thereon by a cap-screw H^5 taking into said hub, a washer h^5 being interposed between the head of the cap-screw and end of the hub. The plate L^2 does not bear against ratchet-wheel L , but is interlocked therewith by means of pin L^4 , extending through a slot l in plate L^2 . Said pin in addition to giving motion to plate M^5 , as heretofore described, is brought into engagement with an end wall of slot l to rotate the plate L^2 at a predetermined period. The plate L^2 is provided with a ratchet segment or rim L^5 , which extends over the periphery of ratchet-wheel L and when carried into operative position by rotation of wheel L is positively actuated by the pawls G^2 and G^3 on the lever G' , the length of segment L^5 being substantially equal to the total length of the row of barring-stitches, although it may be greater, as one or two side stitches may be made after the pawl G^2 engages the segment L^5 , as pawl G^3 being behind pawl G^2 the plate L^2 is advanced one or two teeth before the former is carried out of engagement with ratchet-wheel L . The advantage in employing two pawls is that the feed may be adjusted too fine to permit of the pawl which feeds the main ratchet-wheel riding over the shoulder of the ratchet-segment shown in Fig. 8. By placing one of the pawls in advance of the other the ratchet-segment will be given a positive movement to bring it into position to be engaged by the pawl of the main ratchet feed-wheel. At the beginning of a row of side stitches the plate L^2 remains stationary by reason of its frictional engagement with hub H^4 and until the pin L^4 in traveling to the right through the slot l is brought into contact with the right-hand end wall of said slot, when continued rotation of ratchet-wheel L carries with it the plate L^2 .

l^2 designates an adjustable stop-piece, which may be secured to the plate L^2 over the slot l to adjust the length of the latter, so as to cause the plate L^2 to be brought into position at the proper time.

When the end of a row of side stitches has been reached, the plate L^2 will have been carried into such position that the pawl G^2 , which is in advance of the pawl G^3 , acts upon the segment L^5 to feed it forward, thereby causing the

pawl G^3 , which is of a width equal to the thickness of the wheel L and plate L^2 , to ride over the shoulder l^3 of plate L^2 and out of engagement with the teeth of wheel L and into engagement with the teeth L^5 of segment L^2 . Although the lever G' continues to oscillate, no motion is imparted to ratchet-wheel L , and of course there will be no lengthwise feed of the work-support. The pawls G^2 and G^3 feed the ratchet-segment plate L^2 during the formation of the barring-stitches, the last one or two teeth being advanced by the pawl G^3 until the latter falls therefrom and is caused by its spring g^3 to engage the teeth of wheel L , the latter being first advanced one or two teeth to move the face l^3 of cam I' from beneath the follower E^3 , when the parts will be in position to begin the sewing of the second row of side stitches. During the described movement of plate L^2 the slot l therein is moved to the right, and as wheel L and pin L^4 remain stationary the said pin will be at the left-hand end of said slot when the barring operation is completed, although not necessarily abutting against the left-hand end wall, the only essential being that when the wheel L is fed to form side stitches the pin L^4 shall be brought into contact with the right-hand end wall of slot l to begin the movement of plate L^2 to bring the ratchet-segment L^5 into position to throw pawl G^3 out of engagement with wheel L at the end of the side stitches. During the time that pawl G^2 is out of engagement with teeth L^5 it is held away from plate L^2 and in a plane to engage said teeth at the proper time by a shank g^4 , abutting against a post g^5 , and of course then performs no work. The plate L^2 also carries an adjustable trip-piece L^3 , as shown, to bring the barring mechanism into operative position, as will be more fully hereinafter described.

Having described the means by which the work-support is given a progressive feed lengthwise of a buttonhole, the means by which the needle-bar is given a vibratory movement during the sewing of a row of side stitches, and the means by which such movements are suspended at the end of such periods, I will now describe the means by which the work-support is given a feed transversely to the length of a buttonhole and also a vibratory movement lengthwise thereof to sew the barring-stitches.

To the plate H , I secure two blocks H^7 , which extend upward through slots and are flush with the upper surface of the base-plate. To each of these blocks I fasten, by means of screws h^7 , a slide-plate H^6 , which rests upon the base-plate and provides a suitable bearing-support for the plate H .

Rigidly secured to the base-plate A' is a stud P , having a shoulder P' , which bears against the under side of said plate, the plates H and H' being cut away sufficiently to provide a clearance for the movement of said plates. On the stud P , I mount two

cams Q and R so as to rotate freely thereon, the said cams being secured together by suitable means, as screws r . Mounted on the same stud P is the ratchet-wheel S^2 , secured by pins s^4 to the cam R , so that by rotation of the said ratchet-wheel a rotary movement is imparted to the cams Q and R .

S designates a pawl-carrying arm fulcrumed on the hub of this ratchet-wheel S^2 , and to said arm is secured, by means of a screw s , a pawl S' , held in positive contact with the ratchet-wheel S^2 by a spring s^3 .

S' designates a clamp-nut screwed onto the end of the stud P , and interposed between said nut and the ratchet-wheel S^2 are friction-washers s' .

To give the desired vibratory movement to the plate H lengthwise of the buttonhole, and hence to the work-support during the formation of barring-stitches, I may make the cam-surface Q of the form shown in Fig. 11—that is, with regular recurring elevated and depressed surfaces q^2 q^3 , respectively. Rigidly secured to the plate H is a stud Q' , having a shoulder q bearing against the under surface of said plate, said stud having at its end a roller q' , the whole constituting a follower, which bears against the cam Q and is moved by the rotation thereof.

To feed the work-support transversely to the length of a buttonhole, the cam R is made of the desired shape—for example, that shown in Fig. 11—and to the plate H' , I secure by suitable means, such as screws, a follower R' , which bears against the cam R and is held in positive contact therewith by springs H^8 , each secured at the end h^8 to the base-plate and at the end h^9 to the plate H' .

The pawl-carrier arm S is oscillated, so as to impart an intermittent feed to the ratchet-wheel S^2 , by means of a lever O , secured thereto by means of a screw O^2 , said lever deriving its motion from the lever F^4 , to the slotted end f^6 of which it is secured by a set-screw O' . The slot f^6 of lever F^4 permits the adjustment of lever O to vary the extent of feed of ratchet-wheel S^2 , and hence the closeness of the barring-stitches.

The operation of the mechanism just described is readily understood. By the oscillation of pawl-carrying arm S by lever O the ratchet-wheel S^2 is caused to rotate the cams Q and R . As the first face q^2 is forced against the follower Q' the plate H is moved forward in a direction parallel with the buttonhole, and as the follower clears the face q^2 the spring H^9 , secured at its end h^5 to the base-plate and at its end h^6 to the slide-plate H^6 , retracts the plate H and moves it in a direction opposite to its first movement, the follower Q' dropping into contact with the face q^3 . These alternate forward and back movements of plate H in a direction lengthwise of the buttonhole continue during the rotation of cam Q and are communicated to plate H' , held to plate H , by the gibbs H^3 and H^3 , and by

the plate H', through its hub H², to pinion J, pitman J², and slide-block K to plate N, to which the work-support is attached.

Simultaneously with the above-described vibratory movement of the work-support it is given a feed motion transversely to the length of the buttonhole by means of the cam R contacting with follower R', secured to plate H', it being evident that as said cam rotates the plate H' will be moved against the resistance of springs H⁸ in a direction controlled by the cam-surface and that the feed movement of said plate will be communicated to the work-support through the same parts of the machine as referred to in speaking of the cam Q. The form of cam R shown in Fig. 8 is designed to give a uniform feed to the work-support during the barring operation, and it is so constructed and adjusted with reference to the other parts of the mechanism that the plate H' is fed so as to form barring-stitches first from the center of the buttonhole-slit or from a line in continuation thereof, if the side stitches have been carried beyond the end of the buttonhole, to one side thereof, then back across the buttonhole an equal distance on the other side thereof, and finally back to the starting-point.

To vary the extent of vibratory movement of plate H, and hence the bight of the barring-stitches, without changing the cam Q, I provide an adjustable stop U, fixed to the base-plate and adapted to bear against the edge of plate H or gib H³. By adjusting the stop U the plate H when retracted by spring H⁹, and hence cam Q, will have its backward movement limited by said stop, so that the follower Q' will not rest against the face q³ of cam Q'. By thus limiting the throw of plate H the bight of the barring-stitches may be varied at pleasure.

It is to be understood that during the formation of the side stitches the mechanism just described for giving to the work-support a vibratory movement lengthwise of and a feed movement transverse to the buttonhole remains dormant or inactive. For this purpose the periphery of the ratchet-wheel S² is provided with a blank or plane surface s² for at least the distance of one tooth, and the said wheel is so timed with reference to the mechanism for forming the side stitches that it is brought opposite the pawl S' at the end of the barring operation, so that while the lever O continues to reciprocate no motion is imparted to wheel S², and hence none to the plates H and H'.

To bring the ratchet-wheel S² into position so that it may be fed by means of pawl S' at the end of a row of side stitches, I advance the said wheel by means of a finger T, slotted at t¹, so as to be movable in the supporting-screws t¹ t², which screws hold the finger in position on the block or bracket T', secured to the plate H'. The finger T has loosely pivoted thereto at t³ a pawl T², held normally

in contact with ratchet-wheel S² by means of a spring t².

Secured to the plate L², as before described, is a trip-piece L³, so adjusted on said plate 70 that it is brought into contact with the end t⁴ of finger T to move the latter and the pawl T² during the sewing of the last of the side stitches, so that the ratchet-wheel S² is advanced to bring the pawl S' into contact with 75 the teeth of said wheel at the end of a row of side stitches and when barring-stitches are to be formed. The ratchet-wheel S² then rotates the cams Q and R in the manner described during the formation of barring- 80 stitches and until the blank or plain face s² is brought opposite the pawl S'. Of course the continued rotation of plate L² during the barring operation carries the trip-piece L³ out of contact with the end of finger T, and when 85 this occurs the spring T³ retracts the said finger and brings it into position to be again acted upon by the trip L³ at the proper time. The trip L³ is carried around by plate L² in the movement of the latter, as heretofore described. 90

The several parts of the mechanism just described are so adjusted that during the formation of the barring-stitches the pawl G³ remains in engagement with the segment L⁵ of 95 the plate L² until at or about the time the blank or plain face s² of ratchet-wheel S² is brought opposite the pawl S', so that the progressive feed movement of the work-support does not begin until motion of ratchet-wheel S² is suspended. The ratchet-wheel 100 L and pinion M² make two complete rotations and the pinions M, J, and I one complete rotation for each buttonhole.

In Figs. 16 and 17 I have illustrated a preferred form of the cam-follower for adjusting the length of each row of barring-stitches. The cams R and Q and cam-follower Q' here shown are of the same construction illustrated in Figs. 8 and 11. In order, however, 110 that the length of the row of barring-stitches may be varied, the cam-follower R' is secured to a lever R³, fulcrumed on a stud R², secured to the base-plate A', the plates H and H' being cut sufficiently to provide a clearance 115 for the movements of said plates. The lever R³ is slotted longitudinally at r' and the plate H' at h¹⁰, and into these slots projects a pin R⁴, having a collar r³, which supports the pin between the plate H' and lever R³. The 120 pin R⁴ has its upper end threaded to receive a nut r², which serves to clamp the said pin securely to the lever R³. By adjusting the position of the pin R⁴ toward or from the outer end of slot r' the plate H' is given a 125 greater or less throw by the cam R and any desired length may be given to the row of barring-stitches.

In Fig. 7 I have illustrated the position of the side and barring stitches in a buttonhole 130 produced by the machine heretofore described. In starting the machine the needle

is at the end of the buttonhole-slit or on a line in continuation thereof, as at the point 1. The work-support is then fed progressively lengthwise of the buttonhole, as indicated by the arrow x , to form a row of side stitches, at the end of which the needle is at the center 2 of the buttonhole-slit. The work-support is then fed by the cam R, so that barring-stitches are sewed first from the center to the end of the row of barring-stitches, then across the center to the other end, and finally back to the starting-point, the said support at the same time being given a vibratory movement lengthwise of the buttonhole by the cam Q, so that this set of barring-stitches does not overlap the side stitches. The parts are then in position to sew the other row of side stitches when the work-support is fed in a reverse direction, as indicated by the arrow y , to form the second row of side stitches, when the needle is again brought to the point 1 and the second row of barring-stitches formed in the same manner as the first row; but as the work-support is vibrated in the same direction as before the second row of barring-stitches will overlap the side stitches, as clearly indicated.

In Fig. 14 I have illustrated a modification of the cam Q for the purpose of differently disposing the barring-stitches. I arrange the projections q^2 and recesses q^3 symmetrically on the cam Q and make the recess q^4 —that is, the recess in which the follower Q' rests during the formation of the side stitches—one-half the depth of the recesses q^3 . By such construction when rotation of cam Q brings the first face q^2 —that one immediately to the left of follower Q' of Fig. 14—into contact with said follower the work-support is moved only one-half the distance of the length of a stitch, or from the point 2 to 3, Fig. 15. The next movement of the work-support is the full depth of the recess q^3 , which is twice that of the recess q^4 , and of course carries the stitch for the point 3 to the point 4, and this continues until the starting-surface q^4 is reached, when the last stitch is of the same length as the first. Thus by the construction shown in Fig. 14 both rows of barring-stitches are made to overlap the side stitches, as shown in Fig. 15.

In Figs. 18 and 19 I have shown a modified construction of the cams Q and R to effect the before-described movements of the work-support during the formation of barring-stitches. The cam Q, which imparts the desired jogging movements to the work-support through plate H, is made in the form of a groove, as shown, having inner and outer walls q^5 and q^6 , respectively, which engage the roller q' of the stud Q'. The cam R, which feeds the work-support transversely to the length of a buttonhole, is made in the form of a groove, as shown, having inner and outer walls r^5 and r^6 , respectively, which engage the roller R', mounted on the arm R^3 , secured to the plate H'. By constructing the cams Q and

R in this manner a positive movement in both directions is given the plates H and H' and the use of springs H⁸ and H⁹ is obviated. 70 These cams may be made separate and secured together, as shown in Fig. 10, or cut on opposite sides of a single piece, as shown in Fig. 19. These cams are rotated by the pawl S' and ratchet S² in the manner heretofore 75 described.

Wherever the words "binding-stitches" occur throughout this specification or claims it is to be understood that I refer to the stitches formed on the sides of a buttonhole-slit and not to a special construction of stitch. 80

What I claim as new, and desire to secure by Letters Patent, is—

1. In a buttonhole-sewing machine, the combination with stitch-forming mechanism 85 comprising a needle, and a work-support, mechanism for producing between said stitch-forming mechanism and work-support a relative feed and vibratory movement suitable for forming rows of stitches for the sides of 90 a buttonhole, and mechanism for producing another relative movement for forming barring-stitches at each end of and at substantially right angles to the aforesaid rolls of side stitches, beginning at the center of the 95 buttonhole and extending to one side thereof, then across the end of the buttonhole to the other side thereof, and finally, back to the starting-point, substantially as described.

2. In a buttonhole-sewing machine, the combination with stitch-forming mechanism comprising a needle, and a work-support, mechanism for producing between said stitch-forming mechanism and work-support a relative feed and vibratory movement suitable 100 for forming rows of stitches for the sides of a buttonhole, and mechanism for producing another relative movement for forming barring-stitches at each end of and at substantially right angles to the aforesaid rows of side 105 stitches, beginning at the center of the buttonhole and extending to one side thereof, then across the end of the buttonhole to the other side thereof, and finally, back to the starting-point, and means to vary the extent 110 of said movements, substantially as described. 115

3. In a buttonhole-sewing machine, the combination with stitch-forming mechanism comprising a needle, and a work-support, mechanism for producing between said stitch-forming mechanism and work-support a relative feed and vibratory movement suitable 120 for forming rows of stitches for the sides of a buttonhole, and mechanism for producing another relative movement for forming barring-stitches at each end of and at substantially right angles to the aforesaid rows of side 125 stitches, beginning at the center of the buttonhole and extending to one side thereof, then across the end of the buttonhole to the other side thereof, and finally, back to the starting-point, whereby one set of side and 130 barring stitches is formed, and means whereby these operations are repeated and the di-

rection of the relative feed movements of the sewing mechanism and work-support lengthwise and crosswise of the buttonhole are reversed, thereby forming a second set of side 5 and barring stitches similar to the first, substantially as described.

4. In a buttonhole-sewing machine, the combination with sewing mechanism and a work-support, means comprising a ratchet- 10 wheel for producing a relative feed between said sewing mechanism and work-support lengthwise of a buttonhole, an actuating-pawl for said wheel, means for producing a relative vibratory movement between the 15 sewing mechanism and work-support transversely to the length of a buttonhole, mechanism adapted to operate automatically and periodically to engage and disengage the ratchet-actuating pawl, and mechanism for 20 producing a relative feed between the sewing mechanism and work-support transversely to the length of a buttonhole and simultaneously therewith a relative vibratory movement between said devices lengthwise of a 25 buttonhole immediately after the disengagement of the actuating-pawl from said ratchet-wheel, substantially as described.

5. In a buttonhole-sewing machine, the combination with sewing mechanism and a 30 work-support, of means comprising a ratchet-wheel for producing a relative feed between said sewing mechanism and work-support lengthwise of a buttonhole, an actuating-pawl for said wheel, means for producing a 35 relative vibratory movement between the sewing mechanism and work-support transversely to the length of a buttonhole, means adapted to operate automatically and periodically to suspend the rotation of said ratchet- 40 wheel and mechanism actuated by said wheel to suspend said vibratory movement at the same time, substantially as described.

6. In a buttonhole-sewing machine, the combination with sewing mechanism and a 45 work-support, means comprising a ratchet-wheel for producing a relative feed between said sewing mechanism and work-support lengthwise of a buttonhole, means to actuate 50 said ratchet-wheel, means adapted to operate automatically and periodically to suspend the rotation of said wheel, mechanism to produce a relative vibratory movement between the sewing mechanism and the work-support transversely to the length of the buttonhole, 55 and a cam actuated by said ratchet-wheel to control the mechanism for producing said vibratory movement, said cam operating to suspend such vibratory movement at or about the time that rotation of said ratchet-wheel 60 ceases, substantially as described.

7. In a buttonhole-sewing machine, the combination with sewing mechanism and a work-support, of a pawl-actuated ratchet-wheel, a pinion actuated by said ratchet, 65 mechanism intermediate said pinion, and work-support whereby the said support is fed lengthwise of a buttonhole, means adapted to

automatically and periodically move the ratchet-actuating pawl into and out of engagement with said wheel, a lever connected 70 with the needle-bar of the sewing mechanism by means of a pitman to produce a vibratory movement of the needle-bar, and means actuated by said pinion to adjust the point of connection between said lever and pitman so 75 as to make such connection coincident with the fulcrum of said lever when the actuating-pawl is disengaged from said ratchet-wheel, substantially as described.

8. In a buttonhole-sewing machine, the 80 combination of a needle-bar, means to reciprocate said bar, a lever and means to actuate the same, a pitman connected to said needle-bar and lever, and means to adjust the point of connection between said pitman and lever 85 to a point coincident with the fulcrum of said lever for a predetermined definite period or lengthwise of said lever to a point on either side of its fulcrum, substantially as described.

9. A buttonhole-machine comprising a vibratory needle-bar, a lever for vibrating the same, means to actuate said lever, a pitman intermediate of the needle-bar and said lever and connected loosely with said lever so as to be capable of being adjusted coincident 95 with the fulcrum of said lever for a predetermined definite period or along either arm of said lever, and a cam, and means actuated thereby for adjusting the point of connection between said pitman and lever, substantially 100 as described.

10. A buttonhole-machine comprising a vibratory needle-bar, a lever for vibrating the same, and means to actuate said lever, a pitman intermediate of the needle-bar and said 105 lever and connected loosely with said lever so as to be capable of being adjusted coincident with the fulcrum of said lever or along either arm of said lever, a cam, consisting of three steps, and a lever actuated by said cam 110 and connected with said pitman for adjusting the point of connection between said pitman and first-mentioned lever, substantially as described.

11. A buttonhole-sewing machine, comprising an actuating-pitman and a lever with 115 which said pitman has a sliding connection, a rod for adjusting the point of connection between said pitman and lever to a point coincident with the fulcrum of said lever for a 120 predetermined definite period or lengthwise of said lever to a point on either side of its fulcrum, a second lever longitudinally slotted where it is connected with said rod, and a cam for operating said second lever, substantially 125 as described.

12. In a buttonhole-sewing machine, the combination with sewing mechanism and a work-support, of a ratchet-wheel and mechanism connected therewith to feed said support, a plate having a ratchet-segment extending beyond the periphery of the ratchet-wheel, a lever and means to oscillate the same and two pawls on said lever, one pawl being

in advance of the other and one of said pawls adapted to engage the teeth of said wheel and segment, and the second pawl to engage the segment only, and means to feed the ratchet- 5 segment into position to be engaged by the said second pawl, whereby a positive feed is given said segment to cause the first-named pawl to fall out of engagement with the ratchet-wheel at substantially the end of the 10 sewing of a set of side stitches, substantially as described.

13. In a buttonhole-sewing machine, the combination with sewing mechanism and a work-support, of a ratchet-wheel and mechanism 15 connected therewith to feed said support, a lever having thereon a pawl to rotate said ratchet-wheel, means to actuate said lever, a plate having a ratchet-segment and movable independently of said wheel, a second pawl on said lever in advance of the first-named pawl to engage said segment, and a pin secured to said ratchet-wheel and engaging said segment at a predetermined point in its travel, substantially as described.

14. In a buttonhole-sewing machine, the combination with sewing mechanism and a work-support, of means for producing a relative feed between said sewing mechanism and work-support lengthwise of a button- 25 hole, also for producing a relative vibratory movement between the sewing mechanism and work-support transversely of the length of a buttonhole for the formation of side 30 stitches; independently-operated means for producing a relative feed between the sewing mechanism and work-support transversely to the length of a buttonhole and simultaneously therewith a relative vibratory movement between said devices lengthwise of a button- 35 hole for the formation of barring-stitches, the side-stitch mechanism being operative while the barring mechanism is wholly inoperative, and means actuated by the former to bring the latter into operative position, substan- 40 tially as described.

15. In a buttonhole-sewing machine, the combination with sewing mechanism and a work-support, of a ratchet-wheel and mechanism intermediate said wheel and support, 50 whereby the latter is fed lengthwise of a buttonhole, a second ratchet-wheel and mechanism intermediate thereof and the work-support whereby the latter is moved transversely of the length of the buttonhole and at the 55 same time vibrated in a direction lengthwise of the buttonhole, the second-named ratchet-wheel being dormant while the first is active, means actuated by the first-named wheel to bring the second ratchet-wheel into operative 60 position, and means to actuate said wheels, substantially as described.

16. In a buttonhole-sewing machine, the combination with sewing mechanism and a work-support, of a feed-wheel and mechanism 65 actuated thereby to feed the said support in the direction of the length of a buttonhole, a second feed-wheel and mechanism actuated

thereby to feed the work-support transversely to, and simultaneously therewith vibrate the same in the direction of the length of a buttonhole, said second feed-wheel being dormant while the other is active, a trip-piece actuated by said first-named feed-wheel, means to actuate said feed-wheels, and a pawl-carrying arm to engage said second feed-wheel lying in the path of said trip-piece and actuated thereby after a predetermined length of travel of said first-named feed-wheel, substantially as described.

17. In a buttonhole-sewing machine, the combination with sewing mechanism comprising a vibrating needle-bar and a work-support, of a ratchet-wheel and mechanism intermediate thereof and the work-support to produce a feed of said support lengthwise of a buttonhole, a second ratchet-wheel and mechanism intermediate thereof and the work-support to produce a vibratory movement of the work-support in the direction of the length of a buttonhole and simultaneously therewith a feed movement transversely to the length of a buttonhole, said second ratchet-wheel being dormant while the first-named ratchet-wheel is active, and means actuated by the latter to suspend the vibration of the needle-bar and to bring said second ratchet-wheel into operative position after a predetermined length of travel of said first-named ratchet-wheel, substantially as described.

18. In a buttonhole-sewing machine the combination with sewing mechanism and a work-support, of a slotted plate connected to said support, a cam and means to rotate the same, a cam-follower secured to a lever fulcrumed on a suitable stud, and adjustable 105 means co-operating with the slot of said plate to clamp said lever to said plate, whereby the amplitude of movement of said plate may be varied substantially as described.

19. In a buttonhole-sewing machine, the combination with sewing mechanism and a work-support, of a barring mechanism comprising a plate connected with the work-carrier, a second plate having guides which support the first-named plate, a stud immovably 115 fixed to the bed of the machine, two cams mounted on said stud, means for rotating said cams, and two cam-followers one on each of said plates and each engaging one of said cams, whereby the work-support is fed transversely to and simultaneously vibrated in the direction of the length of a buttonhole, substantially as described.

20. In a buttonhole-sewing machine, the combination with stitch-forming mechanism 125 and a work-support, of a barring mechanism comprising a plate connected to said support, said plate movably supported in guides fixed to a second plate, said second plate, a stud immovably fixed to the bed of the machine 130 and passing through clearance-openings in said plates, said stud having mounted thereon two cams, means for rotating said cams, and two cam-followers one on each of said

plates and each engaging one of said cams, whereby the work-carrier is fed transversely to and simultaneously vibrated in the direction of the length of a buttonhole, substantially as described.

21. In a buttonhole-sewing machine, the combination with stitch-forming mechanism, of a work-support, a plate connected to said support, means to vibrate said plate so as to produce a vibratory motion of the work-support lengthwise of the buttonhole, and means to limit the movement of said plate to vary the bight of the stitches, substantially as described.

22. In a buttonhole-sewing machine, the combination of stitch-forming mechanism, of a work-support, a plate connected therewith, means to vibrate said plate so as to produce a vibratory motion of the work-support lengthwise of a buttonhole, and an adjustable stop fixed to the bed of the machine and against which said plate abuts, whereby the bight of the stitches may be varied, substantially as described.

23. In a buttonhole-sewing machine, the combination with sewing mechanism and a work-support, of a slotted plate connected to said support, a cam to feed said plate transversely to the length of a buttonhole, a slotted arm carrying a cam-follower in contact with said cam, said arm being pivoted to the bed-plate, and a set-screw adjustable along the length of the slots of said slotted plate and arm whereby the length of the rows of barring-stitches may be varied, substantially as described.

24. In a buttonhole-sewing machine, the combination with stitch-forming mechanism and a work-feeding mechanism, of means for controlling said mechanisms for producing side stitches, and independent automatic means for controlling said mechanisms for producing barring-stitches at substantially a right angle to and overlapping a portion of said side stitches while the work is main-

tained in the same relative position to the stitch-forming mechanism.

25. In a buttonhole-sewing machine, the combination with sewing mechanism and a work-support, of means for producing side stitches, means for producing barring-stitches at substantially a right angle to the side stitches comprising a plate connected to the support, a cam-follower secured to said plate, a cam bearing against said follower so constructed as to cause a vibratory movement of said plate in a direction lengthwise of a buttonhole to produce barring-stitches which overlap the side stitches, and means to actuate said cam, substantially as described.

26. In a buttonhole-sewing machine, the combination with sewing mechanism and a work-support, of means for producing side stitches, means for producing barring-stitches at substantially a right angle to the side stitches comprising a plate secured to the work-support, a cam-follower secured to said plate, a cam bearing against said follower so constructed as to move said plate the full depth of the stitch except the first and last stitches, whereby the barring-stitches may be made to overlap the side stitches at both ends of the buttonhole, and means to actuate said cam substantially as described.

27. In a buttonhole-sewing machine, the combination of a needle-bar, a frame in which said bar is mounted, said frame having a stud rotatably adjustable therein and carrying a disk having a stud set eccentrically thereon, a pitman connected to said last-named stud and means to reciprocate said pitman, substantially as described.

In testimony whereof I have signed my name to this specification in the presence of two subscribing witnesses.

JAMES T. HOGAN.

Witnesses:

H. COUTANT,
CHARLES S. JONES.

It is hereby certified that in Letters Patent No. 694,150, granted February 25, 1902, upon the application of James T. Hogan, of Jersey City, New Jersey, for an improvement in "Buttonhole-Sewing Machines," an error appears in the printed specification requiring correction, as follows: In line 94, page 7, the word "rolls" should read *rows*; and that the said Letters Patent should be read with this correction therein that the same may conform to the record of the case in the Patent Office.

Signed, countersigned, and sealed this 11th day of March, A. D., 1902.

[SEAL.]

F. L. CAMPBELL,
Assistant Secretary of the Interior.

Countersigned:

F. I. ALLEN,
Commissioner of Patents.
